UNITED STATES PATENT OFFICE.

CHARLES E. GODLEY, OF DETROIT, MICHIGAN, ASSIGNOR TO EDMUND AND JONES CORPORATION, OF DETROIT, MICHIGAN, A CORPORATION OF NEW YORK.

FOCUSING DEVICE.

Application filed March 16, 1923. Serial No. 625,465.

To all whom it may concern:

Be it known that I, CHARLES E. GODLEY, a citizen of the United States, and residing at Detroit, in the county of Wayne and State of Michigan, have invented a new and Improved Focusing Device, of which the following is a specification.

This invention relates to means for adjustably supporting an electric light bulb in a reflector, and its object is to provide an adjustable mounting of this character which shall be simple in construction, which may be disassembled when desired, and which can be produced at low cost.

15 This invention consists in a cup-shaped member attached to the outer surface of a reflector, a connector sleeve, a spherical clamp adapted to grip the connector tube, and a circular coil spring within the cup to cause the spherical clamp to grip the connector sleeve. This invention further consists in the details of construction illustrated in the accompanying drawing and particularly pointed out in the claims.

25 In the accompanying drawing, Fig. 1 is a longitudinal section of a reflector with this improved focusing device attached to it. Fig. 2 is an end elevation of a spherical clamp.

30 In the drawing, the reflector 1 is of any desired type and has an opening to receive the inner end 2 of the cup-shaped member 3, this end 2 being preferably secured to the reflector by reducing it and then rolling down its outer edge. A ring 4 is secured over the outer end of the cup 3 and has an inwardly turned flange 5.

The tubular connector 6 is of standard size and construction and receives the conductor 7 at one end and the base 8 of the light bulb 9 at the other. Mounted on this sleeve is a spherical clamp 12 consisting of a plurality of parts as shown in Fig. 2 which are held in position by means of an endless circular coil spring 10. As shown in Fig. 1, this clamp when assembled on the connector tube is of less diameter than the reduced inner end of the cup 3 and this reduced end of the cup serves as a seat on which the clamp may slide. The distance from the central transverse plane of the clamp to the flange 5 of the cap is such that the spring 10 obtains a wedging action between the clamp and flange and thus not

only causes the clamp to grip the connector sleeve but also forces it into the reduced end of the cup 3, thus causing the reduced end of this cup to also press the clamp onto the connector tube. But the clamp can also slide around on the spring and the connector sleeve and the bulb it supports may therefore be shifted as desired.

I prefer to leave the opening in the flange 5 sufficiently large to permit the parts of the spherical clamp to be forced in or out, and this is sufficient to permit the spring 10 to be removed or inserted. It is evident that the configuration of this cup 3 may be changed as desired so long as the flange to support the spring 10 is provided.

The tension of the spring and the grip of the clamp are sufficient to hold the connector sleeve and light bulb in position and still permit the clamp to be turned in any desired direction and the connector sleeve to be slid longitudinally to vary the position of the bulb.

I claim—

1. A focusing device for electric light bulbs consisting of a cup-shaped member attached to a reflector, and having an inwardly extending flange at its outer end, a connector sleeve within said cup-shaped member, a sectional spherical clamp within the cup-shaped member and surrounding the connector sleeve, and an endless circular coil spring within the cup-shaped member and engaging the flange at the end thereof and said spherical clamp to cause the clamp to grip the connector sleeve.

2. A focusing device for electric light bulbs consisting of a cup-shaped member attached to a reflector, a connector sleeve within the cup-shaped member, a circumferential clamp within the cup-shaped member and surrounding the connector sleeve, and a tension member extending around the circumferential clamp and positioned within the cup-shaped member and adapted to cause the clamp to grip the connector sleeve, the clamp being slidably positioned by that end of the cup-shaped member that connects to the reflector.

3. A focusing device for electric light bulbs consisting of a cup-shaped member attached to a reflector and having an inwardly extending flange at its outer end, a connector sleeve loose within said cup-shaped

member, a split circumferential clamping device mounted on the sleeve and of smaller external diameter than the diameter of the inner edge of said flange so that the sleeve and clamping device thereon may pass into and out of said cup-shaped member, and an annular coil spring within the cup-shaped

member surrounding and gripping the clamping device and held in position by said flange, said clamping device being of greater outside diameter than the inner end of said cup-shaped member.

CHARLES E. GODLEY.
